MULTIPACTOR OSCILLATOR AND AMPLIFIER

Philo T. Farnsworth, San Francisco, Calif., assignor to Farnsworth Television Incorporated, San Francisco, Calif., a corporation of California

Application February 24, 1936, Serial No. 65,465

19 Claims. (Cl. 250—27)

5 My invention relates to a multipactor oscillator and amplifier, and more particularly to a means and method of utilizing secondary emission for the production of electron multiplication.

This device operates broadly on the principles set forth in my prior application, Serial No. 692,585, filed October 7, 1933, for an "Electron multiplying device", and my prior application, Serial 10 No. 706,965, filed January 17, 1934, for "Methods of electron multiplication".

The present application deals with a multipactor structure and method of operation where multiplication and collection are separated. The 15 present device is, in common with the previous types of multipactors described by me, capable of producing amplification by electron multiplication, and by proper connection can be made to generate self-sustaining oscillations.

20 The primary object of this invention is to provide an improved means and method of abstracting power from a multipactor.

Other objects of my invention are: To provide an oscillator which will convert direct current energy at extremely high efficiency; to provide an oscillator of the high vacuum type which is not subject to the instability and inconsistencies which such phenomena introduce; to provide an oscillator and amplifier which has no 25 heated electrode of the thermionic type, and which is correspondingly free of the difficulties and complications introduced by cathode heating surfaces; to provide an electron multiplier structure which is capable of generating self-sustained oscillations and which may be readily 30 modulated; to provide a means and method of operating a combined multipactor and output structure having a common cathode; to provide a means and method of creating an oscillating 35 cloud of electrons, and a means and method of absorbing power from this cloud; and to provide 40 a simple and efficient multipactor tube.

45 My invention possesses numerous other objects and features of advantage, some of which, together with the foregoing, will be set forth in the following description of specific apparatus embodying and utilizing my novel method. It is therefore to be understood that my method is applicable to other apparatus, and that I do not 50 limit myself, in any way, to the apparatus of the present application, as I may adopt various other apparatus embodiments, utilizing the method, within the scope of the appended claims.

55 Referring to the drawings:

Figure 1 is a diagrammatic sectional view, to-

gether with a multiplier circuit, of a preferred form embodying my invention.

Figure 2 is a sectional view and circuit diagram embodying the tube shown in Figure 1, connected to be a self-oscillator.

Figure 3 is a view, partly in section and partly in elevation, of a multipactor structure utilizing four electrodes describing a cylinder around the central anode.

Figure 4 is a sectional view taken as indicated 10 by the line 4—4 in Figure 3, together with an operating circuit attached thereto.

The operation of my electron multiplier or multipactor, as I desire to call my device, depends upon the transference of energy between 15 an oscillating cloud of electrons and an oscillating E. M. F., usually established between a pair of opposed cathodes, treated or otherwise capable of producing secondary electrons at a ratio greater than unity when impacted by the oscillating electron cloud. If the energy transfer be from the oscillating E. M. F. to the electron cloud, the electrons strike the cathodes and give rise to the secondary electron multiplication phenomena. If, on the other hand, energy is absorbed from the oscillating cloud of electrons, the oscillating field between the cathodes is intensified, and the tube may sustain oscillations in the cathode circuit.

The present invention concerns a device where 20 both of these phenomena are produced in differing but adjacent structures, electrons being passed, preferably through a common cathode, from one to the other.

Considering then, first, the condition where 25 energy is transferred from the applied E. M. F. to the electron cloud, I find that when the period of the oscillating cloud of electrons is close to the resonant frequency of a circuit connecting the cathodes, that the tube acts as a highly efficient electron multiplier and, in many cases, will self-oscillate if energy is withdrawn from the multipactor structure and used, at least in part, to supply the oscillating E. M. F. applied to the cathodes, energy in this case, of course, being supplied from a D. C. source applied to an anode preferably positioned between the two cathodes.

When the period of the oscillating cloud of 30 electrons is close to the resonant frequency of the circuit connecting the cathodes, it is found, experimentally, that the tube generates oscillations which are largely determined by the resonant frequency of the tuned circuit.

The impressed R. F. initiates, by the multipli-

55

cation process, a cloud of electrons of the proper phase to absorb energy from the oscillations. This cloud of electrons would oscillate by itself at approximately the same frequency as that of the circuit, except for the fact that the R. F. itself accelerates the cloud and makes the trip across the tube less than a half period of the tuned circuit. The mere fact that the electrons are speeded up insures that they strike the cathode. The returning group of electrons also make the trip in slightly less than one-half cycle. The result is that the fastest electrons very rapidly get out of phase with the potential. The electron distribution in the cloud, however, reshapes itself at each half period because the rate of multiplication is large compared to the amount of phase shift.

The process results, however, in electrons being fed from the multiplication phase into the opposite phase wherein an electron is decelerated rather than accelerated by the R. F. Electrons in this phase do not strike the cathodes at all, but continue to oscillate between them, delivering energy to the external circuit as they are slowed down by the R. F. If the probability of an electron striking the anode is sufficiently small, equilibrium current results when the electrons are fed from the multiplying phase into the energy-giving phase at the same rate as the electrons are multiplied at the cathode, and electrons of the energy-giving phase never strike the cathode until they have given substantially all their energy to the oscillating circuit.

I may desire, however, as in the present case, not to abstract power directly from the multipactor structure, but to utilize directly a portion of the oscillating cloud of electrons in another structure closely associated with the first, and withdraw the multiplied output from the second structure.

My invention may be more fully understood by direct reference to the drawings, which show an improved type of multiplier structure connected, in Figure 1, as a direct electron multiplier.

The tube itself comprises a conventional type of multipactor, as hitherto described and claimed by me in the applications referred to above, comprising a pair of opposed cathodes, one of which, preferably the end electrode in an envelope 1, is in the form of a cup-shaped cathode 2, the interior of the cup facing the remainder of the structure.

The cup-shaped cathode 2 may be mounted in any convenient manner, such as on a lead 3 passing through a reentrant stem 4 in the end of the tube.

The opposing cathode may conveniently be located at approximately the midpoint of the tube, and comprises a screen cathode 5 extending across the tube and preferably positioned within a cathode cylinder 6.

Between the two cathodes is positioned a multiplier anode 7, preferably in the form of a cylinder whose walls are in the same projected surface face as determined by the walls of the cup 2 and the cylinder 6.

The interior of the cathode cup 2 and the surface of the cathode screen 5 are preferably sensitized so that they will emit secondaries at a ratio greater than unity, when impacted, and this sensitization, which is performed in order that the highest possible ratio may be obtained, may be accomplished by forming the cathodes of silver, oxidizing the silver, and depositing caesium thereon, for example. Such a surface makes a

very efficient secondary emissive surface, with ratios as high as one primary to six secondaries, when impacted at the proper velocity, but I do not wish to be limited to such a formed surface as even untreated nickel has been found to have an emission ratio greater than unity; and any surface, formed or unformed, having such a ratio will be satisfactory, although, of course, multiplication can be accomplished with a lesser number of impacts with the materials having higher ratios.

At the opposite end of the envelope 1 is positioned what may be called a collector cathode cup 8. This cup may be identical in form and shape with the multiplier cathode 2, and between the collector cathode cup 8 and the central cathode cylinder 6 is positioned a second anode 10, identical with the first anode 7.

I prefer to position all five electrodes so that they shall be symmetrical, with the spacing between cathodes 2 and 5 equal to the spacing between cathodes 5 and 8.

Collector cathode 9 is supported on a lead 11 passing through a seal 12 in the end of the tube. Collector cathode 9, however, differs from multiplier cathode 2 in that its inner surface is preferably of a nature that it will not emit secondaries, at least secondary emission will be reduced to a minimum; and I have found that a carbonized nickel surface in this position will prevent, to a large extent, secondary emission.

After the electrodes have been assembled as described, the tube is, of course, baked out, degassed, evacuated, and the surfaces formed on cathodes 2 and 5.

For multiplication, the tube is connected as shown in Figure 1. On the multiplier end radio frequency is fed into the input connection 14 through a blocking condenser 15, to cathode 2 through lead 3, and cathode 2 is connected through a tunable resonant circuit 16 to the screen cathode 5 through suitable ground connections. Anodes 7 and 10 are connected together through separate radio frequency chokes 17 to a D. C. anode source 18, the opposite end of which is also grounded, the positive end of this source being connected to the anodes.

The collector cathode 9 is connected through an output resonant circuit 20 to ground, and the output may be taken from this cathode through blocking condenser 21. All that is necessary to set the tube into oscillation is to energize the anodes 7 and 10, as there will be, in the space between cathodes 2 and 5, a sufficient number of free electrons which are accelerated toward one or both of the cathodes by the potential of the anode, to strike thereon and cause the initiation of secondary emission.

If, then, a radio frequency is applied between the cathodes 2 and 5 and controlled by means of the tuned circuit 16, and the time of flight of the electrons between cathodes 2 and 5 is adjusted by means of placing upon the anode 7 the proper potential so that the time of flight corresponds to the period of the input, oscillations of the electrons between the two cathodes will occur and repeated impacts with the cathodes will take place with the release of secondary electrons at each impact.

Inasmuch as the field between the cathodes is so arranged either by the construction of the cathodes, as shown, or by an external electric field, as has been pointed out in my prior cited applications, certain definite members of traversals will take place before collection by anode 7.

occurs, and a definite multiplication factor will be reached before equilibrium current is arrived at in the tube. Thus, there will occur within the multiplier end of the tube, electron multiplication; and I prefer, with this type of tube, to so adjust the constants on the two cathodes and the anode of the multiplier structure, that a maximum equilibrium current is reached.

The structure just described, however, differs from previous multipactor structures in that the central cathode 5 is apertured. This means that at each time the electron cloud reaches the plane of cathode 5, a certain number of electrons impact and create secondaries which are used to continue the multiplication process, but others of the electrons pass directly through the aperture in cathode 5 and enter the output structure comprising cathode 8, anode 10 and cathode 9.

In this structure, however, conditions are different. The output cathode 9 has been treated to prevent secondary emission, and if cathode 9 is connected to cathode 5 through a tuned circuit 28, the electrons passing through the central cathode 5 will oscillate back and forth between cathodes 9 and 5, and energy will be absorbed from them as they oscillate between cathodes 9 and 5; in other words, in the output structure, energy is being absorbed from the electrons.

30 The advantage gained in taking energy out of the tube in this manner is that phase shift of the oscillating electrons in the output structure is unimportant. In other words, any electrons in the output portion of the tube which get out of phase, and therefore are in a position to absorb energy from the oscillations, strike the cathodes and are absorbed by them, and as the potential on the anodes in each portion of the tube can be adjusted so that the electron oscillation frequency coincides with that of the tuned circuits and with the E. M. F. to be amplified, both structures operate completely in phase.

It will be understood, of course, that the output structure does, in no sense, create electron multiplication; it is in effect a multiplier structure with the exception that the cathode 9 absorbs all electrons striking it, and will not release secondaries. In other words, by using symmetrical structure operating in phase, I have separated 50 multiplication and output. I create the oscillation of the electron cloud and supply power to it, in one structure, with multiplication; and I absorb power from the cloud, without multiplication, in the other structure.

55 I have thus eliminated the necessity within the multiplier structure of developing a large out-of-phase component, in order that power be absorbed from the cloud. In other words, it is necessary, as above explained, in order to create 60 an output from the ordinary multiplier, to absorb power from a component of the electron cloud which is out of phase with the multiplying cloud. In this case only enough power is absorbed to continue multiplication.

65 Such an arrangement leads to a high conversion efficiency, and also leads to a high efficiency self-oscillator. For example, I have shown a circuit in Figure 2 where the output cathode 9 is coupled to the input cathode 2 through a common tuned circuit 22, an intermediate tap 24 being taken from the inductance of the tuned circuit to the central apertured cathode 5. Such a connection causes self-oscillation of the multiplier structure comprising cathodes 2 and 5 and anode 7, with additional power being absorbed in

the output structure comprising cathodes 5 and 8 together with anode 10. This power is fed back to the input structure, and thus the E. M. F. is regeneratively amplified and an extremely efficient oscillator results.

Another structural embodiment utilizing my method of electron collection is shown in Figures 3 and 4. In this tube, opposed multiplying cathodes 25 and 26 are connected through the tunable resonant circuit 16. Cathodes 25 and 10 15 26 are sensitized, as were cathodes 2 and 5, for secondary emission, and in this case the anode is a central spiral 27.

Output cathodes 28 and 29 are also positioned in opposed relation, the four cathodes 25, 26, 28 15 and 29 being positioned to form a cylinder, each cathode, however, being electrically separated, and output cathodes 28 and 29 are also connected by tunable resonant circuit 20. Output cathodes 20 do not emit secondaries and may be of carbonized nickel, as explained above for output cathode 9. The anode 27 is supplied with a positive potential from the anode battery 19.

I also prefer to provide, preferably by means of a focusing coil 30 energized by focusing source 31 under the control of a resistor 32, a feeble magnetic field in the tube with the lines of force axial, so that there will be a progression of the electron oscillation paths in the direction from multiplier cathodes to output cathodes. For example, when radio frequency is applied between the multiplier cathodes 25 and 26, either from a driver or by causing the two multiplying cathodes to become a self-oscillatory structure, the electrons of the proper phase for multiplication tend to oscillate so that they are traveling along the center line connecting the multiplying cathodes, and the electrons oscillating in the phase to give up their energy to the output circuit 20 tend to swing around at right angles to the multiplier cathodes. The application of the magnetic field effectively prevents the output electrons from swinging around, so that they are absorbing power. There is therefore, due to this field, a continuous drift of multiplying electrons over to the output cathodes 28 and 29, where they are collected after giving up their energy to the output circuit.

The main advantage of this type of structure over the structure heretofore described is that 50 all of the current built up by multiplication is eventually converted into oscillating power, thus resulting in a very high efficiency.

Other circuits utilizing the means and method herein described will readily suggest themselves 55 to those skilled in the art, the circuits shown being in the nature of examples only.

I claim:

1. An electron multiplier comprising a pair of opposed surfaces capable of emitting secondary 60 electrons at a ratio greater than unity when impacted, means for causing an electron cloud to oscillate between said surfaces to create repeated multiplying impacts therewith, means for diverting a portion of said cloud into a space apart from that bounded by said surfaces, and means for absorbing power from said diverted portion within said space.

2. An electron multiplier comprising a pair of opposed surfaces capable of emitting secondary 70 electrons at a ratio greater than unity when impacted, means for causing an electron cloud to oscillate between said surfaces to create repeated multiplying impacts therewith, one of said surfaces being apertured to allow a portion of said 75

- cloud to pass therethrough at the time of each impact, and means for absorbing power from the electrons passing through said apertures.
3. An electron multiplier comprising a pair of opposed surfaces capable of emitting secondary electrons at a ratio greater than unity when impacted, means for causing an electron cloud to oscillate between said surfaces to create repeated multiplying impacts therewith, means for dividing said cloud at the plane of one of said surfaces, means for abstracting one of the divided portions from the space bounded by said surfaces, and means for absorbing power from the abstracted portion.
- 15 4. An electron multiplier comprising a pair of opposed surfaces capable of emitting secondary electrons at a ratio greater than unity when impacted, means for causing an electron cloud to oscillate between said surfaces to create repeated multiplying impacts therewith, means for dividing said cloud at the plane of one of said surfaces means for abstracting one of the divided portions from the space bounded by said surfaces, means for absorbing power from the abstracted portion, and a work circuit for utilizing the power obtained.
- 30 5. An electron multiplier comprising a pair of opposed surfaces capable of emitting secondary electrons at a ratio greater than unity when impacted, means for causing an electron cloud to oscillate between said surfaces to create repeated multiplying impacts therewith, means for dividing said cloud at the plane of one of said surfaces, means for abstracting one of the divided portions from the space bounded by said surfaces, means for absorbing power from the abstracted portion, a work circuit for utilizing the power obtained, and means for feeding energy from said work circuit into said oscillating cloud.
- 45 6. An electron multiplier comprising a pair of opposed surfaces capable of emitting secondary electrons at a ratio greater than unity when impacted, means for causing an electron cloud to oscillate between said surfaces to create repeated multiplying impacts therewith, means for dividing said cloud at the plane of one of said surfaces, means for abstracting one of the divided portions from the space bounded by said surfaces, means for absorbing power from the abstracted portion, a work circuit for utilizing the power obtained, and means for utilizing a portion of the energy in said work circuit to cause continued oscillation of said cloud.
- 55 7. An electron multiplier comprising a pair of opposed surfaces capable of emitting secondary electrons at a ratio greater than unity when impacted, means for causing an electron cloud to oscillate between said surfaces to create repeated multiplying impacts therewith, means for dividing said cloud at the plane of one of said surfaces, means for abstracting one of the divided portions from the space bounded by said surfaces, means for absorbing power from the abstracted portion, a work circuit for utilizing the power obtained, and means for feeding back a portion of the energy in said work circuit into said oscillating cloud in the proper phase to continue the oscillation thereof.
- 60 8. In an electron multiplier wherein electrons are directed against a cathode surface to produce secondary emission therefrom, the method of power production comprising oscillating electrons against and away from said surface to produce an electron cloud augmented by secondary electrons at each impact therewith, abstracting
- from the cloud through apertures in said surface a definite proportion of the electrons therein, and absorbing the energy from the abstracted electrons.
9. In an electron multiplier structure wherein an electron cloud is oscillated against and away from a surface to produce secondary emission therefrom upon impact therewith, the method of abstracting power from said cloud which comprises feeding energy to said cloud and abstracting energy from said cloud within different spatial boundaries.
- 10 10. In an electron multiplier structure wherein an electron cloud is oscillated against and away from a surface to produce secondary emission therefrom upon impact therewith, the method of abstracting power from said cloud which comprises dividing said cloud at each impact feeding energy to one portion of said cloud to continue multiplication and abstracting useful energy from the other portion.
- 15 11. In an electron multiplier structure wherein an electron cloud is oscillated against and away from a surface to produce secondary emission therefrom upon impact therewith, the method of abstracting power from said cloud which comprises absorbing energy from said cloud, using said energy to sustain oscillation of said cloud until an equilibrium current is reached, abstracting electrons from said cloud, absorbing energy from said abstracted electrons, and adding said energy to that previously absorbed from said cloud to create regenerative oscillation thereof.
- 20 12. In an electron multiplier structure wherein an electron cloud is oscillated against and away from a surface to produce secondary emission therefrom upon impact therewith, the method of abstracting power from said cloud which comprises feeding energy to electrons traveling along one set of paths, changing the paths, and abstracting power from said electrons while in said changed paths.
- 25 13. In an electron multiplier structure wherein an electron cloud is oscillated against and away from a surface to produce secondary emission therefrom upon impact therewith, the method of abstracting power from said cloud which comprises feeding energy to electrons traveling along a diametrical path, shifting the electrons to a different diametrical path, and absorbing power from said electrons while in said different path.
- 30 14. In an electron multiplier structure wherein an electron cloud is oscillated against and away from a surface to produce secondary emission therefrom upon impact therewith, the method of abstracting power from said cloud which comprises feeding energy to electrons traveling along one set of paths, continuously diverting a portion of said cloud into a different set of paths, and absorbing energy from said electrons while in said different paths.
- 35 15. In an electron multiplier structure wherein an electron cloud is oscillated against and away from a surface to produce secondary emission therefrom upon impact therewith, the method of abstracting power from said cloud which comprises feeding energy to said cloud to maintain oscillation of the cloud across a space in a predetermined path, shifting the oscillation to a different predetermined path, and absorbing power from the electrons in the latter path.
- 40 16. In combination, a pair of opposed electrodes capable of emitting secondary electrons at a ratio greater than unity, a second pair of op-

- posed electrodes incapable of emitting secondary electrons, adjacent said first pair, means for feeding energy to electrons in the space between said first pair of electrodes to produce electron multiplication by cyclical impact therewith, and means associated with said second pair of electrodes for absorbing power from said electrons.
17. In combination, a pair of opposed electrodes capable of emitting secondary electrons at a ratio greater than unity, a second pair of opposed electrodes incapable of emitting secondary electrons, said pairs being alternately disposed to describe a symmetrical space, means for feeding energy to electrons in the space between said first pair of electrodes to produce electron multiplication by cyclical impact therewith, and means associated with second pair of electrodes for absorbing power from said electrons.
18. In combination, a pair of opposed electrodes capable of emitting secondary electrons at a ratio greater than unity, a second pair of opposed electrodes incapable of emitting secondary electrons, said pairs being alternately disposed to describe a cylindrical space, means for
- causing electron oscillation between said first pair of electrodes to cause secondary emission therefrom, means for rotating the oscillation path around the axis of said cylinder, and means associated with said second pair of electrodes for absorbing power from electrons in said rotated path.
19. In combination, a pair of opposed electrodes capable of emitting secondary electrons at a ratio greater than unity, a second pair of opposed electrodes incapable of emitting secondary electrons, said pairs being alternately disposed to describe a cylindrical space, means for causing electron oscillation between said first pair of electrodes to cause secondary emission therefrom, means for rotating the oscillation path around the axis of said cylinder, means associated with said second pair of electrodes for absorbing power from electrons in said rotated path, and means for collecting electrons contacting said second pair of electrodes due to said rotation.
